UNITED STATES PATENT OFFICE.

MORRIS BERNHARD, OF BUFFALO, NEW YORK.

DESIGN FOR A TASSEL.

SPECIFICATION forming part of Design No. 23,483, dated July 17, 1894.

Application filed June 15, 1894. Serial No. 514,699. Term of patent 3½ years.

To all whom it may concern:

Be it known that I, MORRIS BERNHARD, a citizen of the United States, residing at the city of Buffalo, in the county of Erie and State of New York, have invented and produced a new and original Design for Tassels, of which the following is a specification.

This design relates to the ornamentation of tassels, and is illustrated in the accompanying drawing which forms part of this specification and which represents a face view of a tassel embodying the design.

The leading feature of my design consists in a raised frill or ruff extending spirally or obliquely over the body of the tassel.

A represents the braided body of the tassel.

B, B, are transverse frills or ruffs arranged at the ends of the braided body, and C is the spiral or oblique frill extending across the braid from one of the end ruffs B to the other.

D represents the usual loose fibers depending from the body of the tassel.

e is the cord from which the tassel is suspended.

The spiral frill produces in conjunction with the braided body a pleasing effect which is heightened by contrasting the body and frill in color.

Tassels containing my design form a desirable end finish for curtain loops or holders and rope portières, but they may also be employed on fringes and other trimmings.

What I claim is—

The design for a tassel, substantially as herein shown and described.

Witness my hand this 12th day of June, 1894.

MORRIS BERNHARD.
